UNITED STATES PATENT OFFICE.

HARRY HARDWICK, OF PHILADELPHIA, PENNSYLVANIA, ASSIGNOR TO IVINS, DIETZ & METZGER COMPANY, OF PHILADELPHIA, PENNSYLVANIA, A CORPORATION OF PENNSYLVANIA.

PILE FABRIC.

No. 873,744.

Specification of Letters Patent.

Patented Dec. 17, 1907.

Application filed November 2, 1906. Serial No. 341,758.

To all whom it may concern:

Be it known that I, HARRY HARDWICK, a citizen of the United States, residing in Philadelphia, Pennsylvania, have invented certain Improvements in Pile Fabrics, of which the following is a specification.

The object of my invention is to so weave a pile fabric as to provide for a close disposition of the pile loops or tufts together with a more varied coloring of the pattern than can be effected in pile fabrics woven in accordance with the methods now used.

In the accompanying drawings:—Figures 1, 2 and 3 are views of a diagrammatic character showing the different sheddings of the warp threads resorted to in weaving pile fabrics in accordance with my invention; Fig. 4 is an enlarged transverse section, partly on the line *a—a*, Fig. 1, and partly on the line *c—c*, Fig. 1, and Fig. 5 is an enlarged transverse section on the line *b b*, Fig. 1.

My invention relates to that class of pile fabrics in which the pile-forming warp is composed of sets of threads repeated as often as may be necessary to produce a fabric of the desired width, each set comprising a number of threads of different colors, and alternating with a pair or set (hereinafter, for convenience, termed a set) of binding warp threads, the latter being interwoven with suitable weft threads, which serve to confine the pile warp threads and form, with the same and the binding warp threads, a backing fabric from which the pile loops or tufts project.

In weaving such fabrics it is customary to raise one pile-forming warp thread of each set for the insertion of the pile wire, these threads being then depressed to form loops around said wire, and the fine warp threads being operated to form a shed or sheds for the insertion of the binding weft threads above and below the pile warp threads.

The number of pile-forming warp threads in a set does not usually exceed five, and the color range of the pattern is correspondingly limited.

In carrying out my invention, I raise a plurality of the pile warp threads from each set throughout the fabric, or throughout any selected portion of the same, for the insertion of a pile wire, and, as a consequence, there are, wherever such operation takes place, a plurality of pile loops or tufts between ad-

joining sets of binding warp threads. This multiplication of the number of loops or tufts enables me to produce a sufficiently close pile with the use of fine yarns, and I can therefore use more pile threads in a set than is the present practice, and can accordingly enlarge to a corresponding extent the color range of the pattern.

In the drawings, 1 represents part of the swinging lay of the loom, 2 the shuttle race, 3 the reed, 4 the different pile-forming warp threads, 5 and 6 the tying or binding warp threads, 7 the pile wires, 8 and 9, respectively, the upper and lower binding weft threads, 10 the harness cords controlling the pile-forming warp threads, 11 and 12 the heddles controlling the binding warp threads, and 8^a and 9^a, respectively, the shuttles for introducing the upper and lower binding weft threads 8 and 9.

Both of the binding weft threads are, in the present instance, contained in the same shed of binding warp threads, but any desired number of binding warp threads and weft threads may be employed, and these may be interwoven in different ways, and one or more stuffer warp threads may be employed in the ordinary way in connection with each set of pile-forming warp threads, these features of the fabric forming no essential part of my invention, which relates to the manner of shedding the pile-forming warp threads for the insertion of the pile wires, and to the disposition of these threads in respect to the binding warp threads of the fabric.

In the present instance I have shown each set of pile-forming warp threads as consisting of eight threads of different colors, but each set may, if desired, contain a plurality of threads of the same color and instead of shedding these threads in pairs, as shown, a greater number of threads of each set may be simultaneously lifted for the insertion of the pile wire, due regard, of course, being always maintained for the confinement of the binding weft threads 8 and 9 so closely as to insure the tying of the pile-forming loops or tufts firmly into the backing fabric.

Each of the pile threads is composed of a plurality of strands or ends, in order to insure the spread of the pile loops or tufts, necessary to properly cover and hide the backing web of the fabric as shown in Fig. 1.

2
I claim:—

A pile fabric having a backing composed of sets of pile-forming warp threads, alternating with sets of binding warp threads interwoven with binding weft threads, and a plurality of multi-strand pile loops or tufts extending to the face of the fabric between successive weft threads and adjoining sets of binding warp threads, the pile threads of the 10 set extending longitudinally through the

backing web when they are not forming piles.

In testimony whereof, I have signed my name to this specification, in the presence of two subscribing witnesses.

HARRY HARDWICK.

Witnesses:

HAMILTON D. TURNER,
KATE A. BEADLE.
